ELECTROMAGNETIC STAMPING APPARATUS

Johan Albin Jonsson, Stockholm, Sweden, assignor to Telefonaktiebolaget L. M. Ericsson, Stockholm, Sweden, a company of Sweden

Application July 16, 1935, Serial No. 31,626
In Sweden June 6, 1934

16 Claims. (Cl. 101—287)

The present invention relates to an electro-magnetically operated or controlled impression mechanism and particularly to a mechanism of the type which is used for workmen's time recorders. It is known to build recording apparatus so that the impressing is effected upon closing of a circuit by an electromagnet, the energizing circuit of which is closed either manually by means of a push button or the like or 5 automatically by an inserted card which, upon insertion, directly engages a contact. In workmen's time recorders the first mentioned arrangement has, however, the inconvenience that it requires the use of both hands of the operator. This is very inconvenient particularly if a 10 considerable number of workmen pass, having packages or tools in their hands. The closing of the said circuit by means of an inserted card has the inconvenience that the closing and opening 15 of the circuit is effected slowly whereby the contacts are soon destroyed and the current consumption becomes unreasonably great.

Such inconveniences are avoided according to the present invention by providing a contact arrangement for closing and opening the circuit through an electromagnetic arrangement for driving or controlling the apparatus, is controlled by a toothed wheel or ratchet wheel which cooperates with a stepping mechanism adapted to 20 be advanced alternately on the closing of the circuit by means of an arm arranged in the path of the time card and adapted to be actuated by the latter upon its insertion in the apparatus and alternately on the breaking of the 25 circuit by means of a lever or the like connected with the electromagnetic arrangement.

The moving force proper may, for instance, consist of a constantly rotating shaft which by 30 means of an electromagnet is momentarily coupled to the apparatus at each stamping operation, but generally it is more preferable to let the electromagnetic arrangement supply also the energy necessary for operating the apparatus. One important reason for selecting the latter embodiment is the fact that on account of 35 the momentary circuit closing and circuit opening effected according to the present invention considerably greater currents can be allowed in the circuit of the electromagnet of the new apparatus than in previously known apparatus. This advantage is utilized for providing a simpler and more solid construction of the mechanism of the new apparatus than in that of manually operated apparatus and in addition the

stamp may be effected more rapidly than before.

An embodiment of the invention is shown by way of example on the accompanying drawings. Figure 1 shows a detail on a larger scale of the central portion of the apparatus including the contact mechanism and its co-operating parts, as viewed from the left side of the apparatus. Figure 2 is a rear view, partly in section, of the same portion of the apparatus according to Figure 1. Figure 3 is a rear view of the entire apparatus with the casing partly cut away to show the mechanism. Figure 4 shows the apparatus in the same manner but viewed from the left, and Figure 5 as viewed from the right. In Figures 3 to 5 some details having no connection with the invention have been omitted to make the figures more clear.

At the upper part of the recess 1 intended for the card holder are arranged a hole finder 2, a puncher 3 and a feeler arm 4. When a workman's time card is inserted in the card holder its lower edge engages the feeler arm 4 which is turned clockwise in Figure 1 until the card can pass by the rounded-off end of said arm. The upper end of a spring 5 is connected to the rear part of the feeler arm 4, the lower end of said spring being connected to a short lever secured to an arm 6 on which the hole finder 2 is secured. If the arm 4 is turned clockwise, the spring 5 pulls the arm 6 with it, turning it around the pivot 6a, and if the hole finder engages the card it is stopped together with the arm 6, and the spring 5 is being tensioned. Until the hole finder 2 finds a hole in the card it slips along the same, but at the moment when the hole finder snaps into a hole and arrests the card the latter will press down the hole finder 2 further so that the depending end 7 of the arm 6 engages a pin 8 Fig. 2, extending laterally from a side plate 9. The latter is rotatable about a pivot 10 against the action of a spring 16. On the pivot 10, which is secured at both of its ends to the frame of the apparatus, and inside the side plate 9 is secured a ratchet wheel 11 which is adapted to co-operate with a feed pawl 12 which is rotatable about a pivot 13 against the action of a spring 14. The pivot 13 is at its rear end (Figure 2) secured in a side plate 15 which is parallel with the side plate 9 and held in position at a suitable distance from the latter by means of pins provided with spacers.

When the arm 7 engages the pin 8, according to the above, the pin 8 together with the side plates 9 and 15 will be turned counter-clockwise

(Figure 1) against the action of the spring 16. During this movement the feed pawl 12 engages the ratchet wheel 11 and turns the same counter-clockwise thereby causing one of its teeth against which a hook-shaped projection 18 of an arm 17 rests, to slip away whilst the projection 18 snaps into the space between two teeth until it contacts with a stop pin 22. The arm 17 is a two-armed lever which is rotatable about a pivot 19 and, at its other end, is provided with a hammer 20 of insulating material which presses against a contact spring 21, the lever being held by said spring in its position of rest against the point of a tooth of the ratchet wheel 11.

Laterally of the lever 17 and on the same pivot 19 is arranged a similar lever 23 having a projection 24 which also co-operates with the ratchet wheel 11. The point of the projection 24 is positioned about one third of the width of a tooth 0 to the right of the point of the projection 18 as viewed in Figure 1. The lever 23 bears against the contact spring 26 by means of a hammer 25 of insulating material and is held by said spring in its position of rest against the stop pin 22. The stop pin is so positioned that the projections 18 and 24 can not reach the bottom of the spaces between the teeth of the ratchet wheel 11 whereby the arrangement becomes more easy to be operated. The contact springs 21, 26 are connected in series with a powerful electromagnet 27 and an external current source.

In the position of rest of the arrangement the contacts of the contact springs 21, 26 are separated, as shown in Figure 1, and the circuit through the electromagnet is interrupted. If the ratchet wheel 11 is advanced one step counter-clockwise according to the above, the projection 18 will first reach the stop pin 22 whereby the lever 17 is turned clockwise and the contact spring 21 bends to the right (Figure 1) into contact with the contact spring 26 whereby the circuit through the electromagnet 27 is closed. The electromagnet 27 attracts its armature 28 which turns clockwise about its pivot 29. The armature is designed to form a bridge between two triangular side plates 30. These are also connected by means of a bracing 31 which serves as a rest for a stamping hammer 32 turnable on the spindle 29 as well as for a lever 33 which is also turnable on the spindle 29. The stamping hammer 32 is pressed against the bracing 31 by a helical spring 34 which is secured in an eye 35 arranged at the rear of the bracing 31 (i. e. to the left according to Figure 4). In said eye 35 is also secured a helical spring 36 which holds the bracing 31 and thus also the armature 28 in its position of rest counter-clockwise. The helical spring 34 has the effect, that in the clockwise end position of the armature the hammer is flung further forward on account of its inertia and is thereafter immediately pulled back to bear against the bracing 31. Hereby the difficulty found in some other stamping apparatus, viz. that the hammer interferes with the movement of the digit wheels is eliminated.

The lever 33 positioned laterally of the stamping hammer 32 (Figures 3 and 4) is connected with the bracing 31 by means of a riveted-on bolt 37 passing through the bracing and over which is threaded a helical spring which has the effect of damping the movements of the lever 33. At the upper end of the lever 33 there is provided a recess 38 which is adapted upon clockwise movement of the lever to embrace a tooth of the ratchet wheel 11 in the end position of the latter

when the feed pawl 12 rests against the pin 22. As to be seen in Fig. 4, the recess 38 in the lever 33 has the same contour line as a tooth of the ratchet wheel 11. This recess can therefore embrace in the right end position of the lever 33 the tooth which is shown most to the left in Fig. 1. Thereby the ratchet wheel 11 is prevented from further rotation counter-clockwise. This is a measure of safety intended to prevent the ratchet wheel from rotating too far on account of its inertia. When during its clockwise movement the lever 33 has arrived to the above position it engages a pin 39 secured between the side plates 9 and 15 and carries the pin 39 together with the side plates 9 and 15 counter-clockwise. The feed pawl 12 is hereby caused to advance the ratchet wheel 11 until its engages the pin 22.

Previously to the movement of the lever 33 the arm 7 has in the manner described above engaged the pin 8 and turned the side plates 9 and 15 clockwise causing the feed pawl 12 to advance the ratchet wheel 11. When the latter reaches its intermediate position and the circuit is closed between the contact springs 21, 26 the lever 33 will advance the ratchet wheel further according to the above so that the point of the surface 24 drops down behind the next tooth the two arms 17 and 23 being thereby brought back to the same mutual positions as in Figure 1. Thus the circuit through the electromagnet is closed only during the short time which the armature and the parts secured thereto need for their movement and is thereafter interrupted instantaneously since the teeth of the ratchet wheel 11 have such a shape that the projection 24 can drop freely into the space between the teeth after having passed the point of a tooth.

Immediately upon being deenergized the electromagnet 27 releases its armature 28 permitting the armature together with the parts 30 to 33 to be turned back counter-clockwise by the spring 36. The apparatus is now again in its position of rest, and on inserting the next time card the operation described above is repeated.

When a time card in which a hole has not previously been punched is inserted in the card holder and in the recess 1, it cannot be arrested by the hole finder 2 but continues its movement until it engages a feeler arm 88 which together with a sector 89 is adapted to turn about a pivot 90. The sector 89 is then turned clockwise according to Figure 1 so that an engaging surface 91 pushes away a pin 92 secured to the side plate 9. Hereby the feed pawl 12 is caused to turn the ratchet wheel 11 and as a consequence the circuit through the electromagnet is closed as described above. The sector 89 with its engaging surface 91 also serves to hold the side plates 9, 15 in a definite position of rest counter-clockwise when the apparatus is not in use. For said purpose there is arranged in the path of the arm 88 a stop pin 93.

In order to prevent the effecting of more than one stamping for each depressing of the arm 4 the latter is provided with a projection carrying a pin 94 (Figure 1) which engages in a corresponding fork in the upper end of a lever 95 which is pivoted on a pin 96 secured in the frame. Below said pin 96 there is arranged in the lever 95 an opening in which engages a pin secured on a lever 97. The lever 97 is turnable about the pin 96 and is provided at its lower end with an engaging surface 98. In the pin 96 is secured a spring 99 which is carried about

the pin 96 and bears against the lever 95 at the other side of said pin.

When a time card is inserted in the apparatus and presses the arm 4 clockwise the pin 94 turns 5 the lever 95 through a certain angle counter-clockwise, the lever then carrying with it the lever 97 so that the lower end of the latter enters the path of the pin 8. When the pin 8 is displaced to the left according to Figure 1 by the 10 arm 7 it does not yet reach the lever 97, but at the moment when the armature 28 is attracted the pin 8 together with the side plates 9, 15 is turned further counter-clockwise on account of the lever 33 engaging the pin 39. The pin 15 pushes away the lever 97 against the action of the spring 99 secured to the carrying pin so that the pin 8 passes the lower end 98 of the lever. When immediately thereafter the armature 28 is restored to its resting position by 20 spring 36 the pin 8 will be arrested by the engaging surface 98. In this position the pin 8 is out of reach for the lever 7 and the pin 92 is out of reach for the engaging surface 91. Thus no further stamping can be effected until 25 the card has been pulled up so far that the arm 4 has returned to its position of rest. When the arm 4 is returned to its position of rest the arm 95 is turned clockwise carrying with it the arm 97 so that the pin 8 slides off the surface 98 and returns to its position of rest together with its side plates 9, 15.

The movement of the armature 28 and the side plates 30 is utilized for effecting the punching of the holes in the inserted time cards. For 35 this purpose there is pivotally secured to the left side plate 30 according to Figure 3 a link 40 which at its upper end is pivotally secured to a pin 41 on a U-shaped yoke 42. The latter turns about a spindle 44 secured in the frame 43. The 40 other arm of the yoke 42 is at its upper end pivotally connected with the puncher 3 which is horizontally displaceable through two holes in the upper end of the frame 43.

When the armature 28 is attracted the pull 45 link 40 will evidently be pulled downwards turning the yoke 42 clockwise according to Figure 1 whereby the puncher 43 is advanced. When the electromagnet 27 is deenergized and the armature 28 is pulled back by the spring 36 the link 50 will in a corresponding manner pull the puncher back to its initial position.

To the left side plate according to Figure 3 is also secured an arrangement for feeding the 55 coloured ribbon said arrangement comprising a laterally extending pin which at the reciprocatory movement of the side plate 30 carries with it a notched disc turnably secured on the frame part 45 which notched disc in turn carries with it a lever 46 so that said lever is turned back and forth through a small angle. The 60 lever 46 is secured to a vertical spindle 47 which at its upper end is provided with a stepping mechanism for the coloured ribbon rolls.

The right side plate 30 (according to Figure 65 3) is rigidly connected by means of a pin 49 with an arm 48 adapted to turn about the spindle 29. Said arm 48 is at its upper (outer) end provided with a cross pin 50 which for the purpose of shifting the coloured ribbon from one 70 colour to the other is adapted to co-operate with a knife edge 51 on a curve disc 52 turnably arranged on a pin 53 secured in the frame of the apparatus. On the side facing the knife edge the pin 50 is also shaped to form a knife edge in

order that it shall not be able to stop in an intermediate position. In addition, the curve disc 52 is provided with an opening 55 acting as a coupling member for a pin 56 secured in a triangular disc 57 arranged inside the curve 5 disc 52 and also turnable on the spindle 53. The curve disc 57 is actuated at its right end (Figure 4) by a spring 54 secured in the frame, the purpose of said spring being to counter-balance the weight of the curve disc 57 together 10 with the parts attached thereto whereby the mechanism becomes more easy in operation. By means of a link 58 pivotally secured at both ends the curve disc 52 is connected with a lower curve disc 59 which is turnable about a pin 60 15 and carries at its opposite end, reckoned from the link 58, a so called semaphore 61 the upper end of which is provided with two differently coloured surfaces which are visible from without to indicate which one of the colours of the 20 coloured ribbon is in use for the moment.

When the coloured ribbon is to be shifted to another colour the bell crank lever 62 (to the right in Figure 4) is actuated in advance by a pin 63 appertaining to a so-called programme work of 25 known construction. The bell crank lever 62 then turns clockwise about the pin 64 and lifts by its longer arm the freely depending pendulum 65 so that a horizontal pin 66 on the lower portion thereof slides up along a sloping surface on the 30 curve disc 59 and passes the point 67. At the predetermined moment the pendulum drops and slides down at the side of the point until it engages the curve disc 59 turning the latter so far that the curve disc 52 is turned counter-clockwise 35 by means of the pin 58 until the upper edge of the opening 55 engages the pin 56 and the knife edge 51 arrives below the opposite knife edge of the pin 50. The pendulum or the programme work respectively is not powerful enough to complete the shifting operation because an unreasonably strong and expensive construction would be required for such purpose. The shifting proper is instead effected by the electromagnet when attracting its armature 28. The arm 48 then 45 turns clockwise according to the above so that the pin 50 hits the upper sloping surface of the knife edge 51 with great force. Hereby the curve disc 52 is turned farther counter-clockwise carrying with it by means of the pin 56 the rear disc 50 57, to the upper left corner of which (according to Figure 4) is pivotally secured a link 68 the upper end of which embraces by means of a lateral opening a pin 69 of the coloured ribbon holder thus pushing the latter downwards. 55

The next time when the programme work turns the bell crank lever 62 clockwise about the pivot 64 the pendulum 65 is lifted anew this time passing over the edge 67 to the right whereby the curve disc 59 is turned clockwise. In order that 60 the pendulum shall not "derail" causing the mechanism to become inoperative there is provided a holder 70 co-operating with the pin 66.

Through the clockwise movement of the curve 65 disc 59 the link 58 is pressed upwards turning the curve disc 52 clockwise to the position shown in Figure 4 in which the knife edge 51 is positioned above the knife edge of the pin 50. When the electromagnet attracts its armature 28 the arm 70 48 is turned clockwise as before and the pin 50 presses the lower sloping surface of the edge 51 forcefully upwards, the opening 55 carries with it the pin 56 and the curve disc 57 is turned clockwise. The link 68 is thus moved upwards and 75

pushes the pin 69 of the holder for the coloured ribbon upwards.

For the purpose of making the movements of the disc 57 more marked there is provided a spring arrangement consisting of an S-shaped spring 72 secured to the lower corner 71 of the disc 57 the other end of the spring bearing against a pin 73 secured in the frame. The arrangement is so dimensioned that the pin 71 must pass the connecting line between the pins 53 and 73 each time the coloured ribbon is shifted and that the two end positions of the pin 71 lie symmetrically with respect to said line. Thus during each movement of the disc 57 the spring 72 will first be compressed and thereafter expand again on the other side of said line accelerating the movement of the disc 57.

In order to obtain a more even leading of the armature 28 the mechanisms described above are so dimensioned that their movements do not take place absolutely simultaneously, the operation for shifting the position of the coloured ribbon (if this operation is to take place) being started first and then the punching of the card, whereafter the stamping hammer is flung against the card. At the end of the clockwise movement of the armature the breaking of the circuit is effected and during the return movement of the armature the feeding of the coloured ribbon.

In the event of the apparatus becoming currentless through a fault in a connecting wire or for some other reason there is a possibility of temporarily operating the apparatus manually. For this purpose a handle 74 can be attached by means of a bayonet clutch to a shaft 75 on which is secured a disc 76 which by a helical spring 77 is normally pressed in a clockwise direction. In the disc 76 is further fastened a helical spring 78 the other end of which is fastened to an arm 79 which is adapted to turn on a pin 80. To the arm 79 is secured an abutment piece 81 which when the arm 79 moves counter-clockwise according to Figure 5 engages an abutment piece 82 secured on a bell crank lever 83 which is adapted to turn on a pivot 84 against the action of a spring 85. At the upper end of the arm 79 is secured a pin 86 which when the arm 79 turns counter-clockwise can carry with it a lever 87 rigidly secured to the armature 28.

When the handle 74 has been attached to the shaft 75 and is pressed downwards the disc 76 will initially turn through a small angle counter-clockwise against the action of the springs 77 and 78 while the arm 79 is prevented from following on account of the abutment 81 being arrested by the abutment 82. When pressing down the handle harder the pin 88 on the disc 76 will engage the bell crank lever 83 turning the same clockwise whereby the abutment 82 is turned away and the arm 79 is suddenly pulled to the left by the spring 86 and hits the arm 87. At the moment when the handle is released the mechanism is pulled back by the springs to the position of rest shown. The advantage of this arrangement over the arrangement of simply placing the handle directly on some part that is rigidly connected with the armature 28 is that a marked impulse is obtained and that every attempt to effect a faulty stamping or other manipulations not allowed is prevented.

I claim:

1. Impression mechanism with electromagnetic driving or controlling arrangement, particularly for workmen's time recorders, characterized in that a contact arrangement for closing and opening the circuit through an electromagnetic arrangement for driving or controlling

the apparatus is controlled by a toothed wheel or ratchet device which cooperates with a stepping mechanism adapted to be advanced alternately on the closing of the circuit by means of an arm arranged in the path of the time card and adapted to be actuated by the latter upon its insertion in the apparatus and alternately on the breaking of the circuit by means of a lever or the like connected with the electromagnetic arrangement.

2. Impression mechanism according to claim 1, characterized in that the stepping mechanism consists of two mutually connected side plates arranged at opposite sides of the ratchet wheel and freely rotatable on a spindle each plate being provided with a number of lateral pins of which one forms the pivot for a feed pawl cooperating with the ratchet wheel whilst two others serve as abutments for an arm actuated by the time card and the lever actuated by the electromagnet.

3. Impression mechanism according to claim 1, characterized by a quick-break arrangement the contacting arrangement of which is designed as two contact springs which in their positions of rest press each against an appertaining bell crank lever the other ends of said levers being so formed that in their positions of rest one bell crank lever will bear against the point of a tooth of the ratchet wheel and the other enter into an adjacent space between the teeth.

4. In a mechanism according to claim 1 two contacts adapted for quickly closing and opening the circuit, two bell crank levers adapted to actuate said contacts and provided with projections cooperating with the teeth of said ratchet device, said teeth shaped so as to permit any of said projections to freely move into the space between two subsequent teeth after having passed the point of one tooth of said device during a relative movement of said device and said projection.

5. In a mechanism according to claim 1, said last mentioned lever provided with a recess adapted to be swung into the path of the teeth of said ratchet device for stopping said device.

6. In a mechanism according to claim 1, two cooperating contacts for quickly closing and breaking the circuit, two levers pivotally arranged for actuating said contacts, said levers provided with parts adapted to engage said ratchet device and to enter any of the spaces between its teeth, whereby their movement is controlled, and means for preventing any said part to move down to the bottom of said space when entering it.

7. In a mechanism according to claim 1, a feed pawl arranged to cooperate with said ratchet device, rotary means pivotally supporting said pawl, two levers pivotally arranged for controlling said contact arrangement, said levers provided with parts engaging said ratchet device, whereby their movement is controlled, and common means for limiting the movement of said parts into said ratchet device and of said pawl upon entering the space between subsequent teeth of said ratchet device.

8. In a mechanism according to claim 1, movable means for finding a hole in a time card arranged close to its path, elastic means connecting said hole finding means with said arm arranged in the path of the time card, said arm moving said hole finding means upon insertion of a card towards said card and in engagement

- therewith, thereby tensioning said elastic means while the card is further moved along its path, means operatively connected with said hole finding means and adapted to advance said ratchet device under the action of said tensioned elastic means when said finding means enter a hole of said card.
9. A device for printing workmen's time cards comprising an electromagnetic device for actuating the printing stamp, a contact arrangement controlling the electric circuit for energizing said device, means for quickly opening and closing said contacts, a toothed device for actuating said means, a first member arranged in the path of said card adapted to be moved by it, a second member arranged in said path behind said first member and spaced therefrom, a feeding pawl adapted to engage and advance said toothed device thereby causing a closing and subsequent opening of said circuit, and means operatively connected with said second member for operating said pawl if an inserted card reaches and moves said second member.
10. In a mechanism according to claim 9, a puncher for punching a hole in said card, means for operating said puncher, depending upon the position of said second member, so that a hole is punched in said card at a desired place when said card has reached and moved said second member.
11. In a mechanism according to claim 9, a puncher for punching a hole in said card, means for operating said puncher to be actuated by said electromagnetic device when energized.
12. In a mechanism according to claim 9, a puncher for punching a hole in said card, means for operating said puncher to be actuated by said electromagnetic device when energized, and a device for feeding a coloured ribbon in front of said printing stamp, said feeding device operated by said electromagnetic arrangement.
13. Stamping apparatus according to claim 1, characterized by the provision of an armature actuated by an electromagnet and a restoring spring, said armature being connected with arms or side plates journaled on a spindle and radially extending therefrom, driving arrangements for hole punching, stamping, and coloured ribbon feed being secured to said side plates.
14. A stamping device, in particular for workmen's time cards, comprising a printing stamp, an electromagnetic device for operating said stamp, a contact device for closing and opening an electric circuit controlling the energization of said electromagnetic device, means for actuating said contact device, a toothed member for operating said last mentioned means, a ratchet device for alternately advancing and stopping said toothed member, a path for inserting a card and a member arranged in said path to be moved by a card when inserted, means operatively connecting said latter member with said ratchet device, advancing said latter device and causing thereby the closing of said contact if a card is inserted in said path, whereby said electromagnet is energized and said stamp made to print said card, and means operatively connected with said electromagnetic device for completing the movement of said tooth member after it has caused the closing of said contacts, thereby causing the reopening of said contacts.
15. A stamping device, in particular for workmen's time cards, comprising a printing stamp, an electromagnetic device for operating said stamp, a contact device for closing and opening an electric circuit controlling the energization of said electromagnetic device, means for actuating said contact device, a toothed member for operating said last mentioned means, a ratchet device for alternately advancing and stopping said toothed member, a pawl adapted to engage said toothed member, means for movably supporting said pawl in operative proximity to said toothed member, a path for inserting a card, a member arranged in said path adapted to be moved by said card when inserted, means for moving said supporting means when said latter member is moved by said card, thereby causing said pawl to engage and advance said toothed member, and means connected with said printing stamp adapted to move said supporting means, thereby causing said pawl to complete the advancing of said toothed member.
16. In a mechanism according to claim 14, additional means connected with said printing stamp, said means adapted to be operated by hand.

JOHAN ALBIN JONSSON.
